HYDRAULIC CIRCUIT

Gunnar A. Wahlmark, Rockford, Ill.

Application May 15, 1937, Serial No. 142,887

9 Claims. (Cl. 60—52)

The invention relates to a hydraulic circuit and has as a general object to provide a novel and improved circuit for supplying operating fluid to a hydraulic motor at selectively different rates for actuating a member driven by the motor at different speeds, in opposite directions and under different loads.

A more particular object of the invention is to provide a novel and improved hydraulic circuit particularly adapted for supplying operating fluid to a reversible hydraulic motor at relatively different rates and directions of flow for reciprocating a tool or work support of a machine tool at different speeds and under different loads.

Another object of the invention is to provide a new and improved hydraulic circuit for a machine tool which is unusually flexible in its adjustments and operation so as to make readily obtainable a large variety of cycles of operation of the machine tool.

Yet another object is to perfect a hydraulic circuit operable to drive a member in opposite directions and at different rates of speed in which an individually operable remote control valve is provided for controlling each the starting and stopping of the member, the particular rate of travel of the member, and the reversal of the member.

A further object is to perfect a hydraulic circuit for driving a member through various cycles of operation, including starting and stopping of the member, movement in a forward or return direction, and feed or traverse rate of movement, which includes hydraulically actuatable main governing valve mechanism controlling the direction and volume of flow of operating fluid in the circuit, and a plurality of independently operable remote control valves, each being electrically actuated and independently associated hydraulically with the governing mechanism for controlling one of the steps in the cycle of operation of the member.

Still a further object is to provide a hydraulic circuit of the character described in which dwell of the member prior to reversal may be obtained without the addition of valve means not required for a cycle of operation omitting dwell.

Yet a further object is to perfect a hydraulic circuit capable of driving a member at three automatically obtained feed rates of movement.

Other objects and advantages will become apparent from the following detailed description taken in connection with the accompanying drawings, in which:

Fig. 1 is a piping diagram of a hydraulic circuit embodying the features of the invention.

Fig. 2 is a schematic diagram of the hydraulic circuit shown in Fig. 1.

Fig. 3 is a fragmentary diagrammatic view of a portion of the circuit modified to obtain a dwell.

Though the hydraulic circuit is susceptible of various modifications and alternative constructions, it is shown in the drawings and will hereinafter be described in a preferred embodiment, but it is not intended that the invention is to be limited thereby to the specific construction disclosed, but it is intended to cover all modifications and alternative constructions falling within the spirit and scope of the invention as defined by the appended claims.

While a hydraulic circuit embodying the features of the invention might be employed in a variety of devices and through a hydraulic motor 20 to actuate a member at different speeds and through different cycles, the hydraulic circuit is for purposes of disclosure herein shown and will hereinafter be described as particularly adapted for driving a table or support of a machine tool. 25 Such a table or support is here represented at 9 (Fig. 2) and is adapted to be driven to the left from its normal or stop position to the limit of its movement in that direction, and is then reversed and returned to its normal position. In 30 such reciprocation, the table is normally driven at different speeds. One such speed is a high speed which is imparted to the table while the tool and the work are out of engagement and is commonly called "rapid traverse." This traverse 35 rate is employed in either forward or return movement of the table, while the work and the tool are being brought together or while they are being separated. Another such speed is a substantially lower speed during which the tool 40 is in engagement with the work and performs its cutting operation. This speed must be maintained with a high degree of smoothness and uniformity as compared with "rapid traverse" and is commonly known as "feed." This "feed" 45 rate of movement may be varied and provision is here made for obtaining three feed speeds. The table may also be arrested temporarily at some point other than its normal stop position, usually at the end of its forward movement, and 50 this temporary arrest is known as "dwell." Provided the circuit is flexible enough, movement of the table at these speeds and to the right or to the left may be arranged in any predetermined sequence to obtain the cycle of movement 55 desired.

To impart a desired cycle of movement to the table, the hydraulic circuit herein comprises generally a reversible hydraulic motor 10, a unitary pressure generating and control device generally designated 11 (see Fig. 1) and remote control valve means of unique construction for governing the operation of the pressure generating and control device. The pressure generating and control device is housed in a single casing 12 and comprises pumping mechanism (see Fig. 2) composed of a large output constant displacement pump 13, commonly known as a "traverse" pump, and a low output variable displacement pump 14, commonly known as a "feed" pump, and governing mechanism composed of a plurality of valve means directly associated with the pumping mechanism for controlling the fluid discharge from the device. Pump 14 is of unique construction and is associated with the traverse pump and the motor in a unique manner so that all fluid flowing to the motor passes through the pump 14 and so that the pump 14 functions or acts in a variety of ways upon different quantities of fluid supplied by the traverse pump and thus determines the quantity of fluid supplied to the motor, though both pumps continue to operate. More particularly, under one condition the pump 14 functions to discharge no fluid whatsoever with the result that the motor remains stationary, while under another condition, the pump 14 functions to meter and to boost the pressure of a portion of the fluid supplied by the traverse pump thus to drive the motor at a "feed" rate, and, while under yet a different condition, the pump 14 functions to pass all of the fluid supplied by the traverse pump without acting thereon with the result that the motor is driven at a "traverse" rate.

Of the plurality of valve means constituting the governing mechanism, a valve means generally designated 15 governs the volume of fluid discharge from the device and includes valves governing the conditions determining the manner in which the pump 14 functions and a valve controlling the displacement of the pump 14. Other valve means generally designated 16 governs the direction of fluid discharge from the device 11 and consists of a single valve, while a third valve means generally designated 17 limits the pressure of the discharge and consists of two valves, one in the nature of a high pressure relief valve and the other in the nature of a low pressure limit valve or circuit locking valve. The governing mechanism and the pumping mechanism, as previously stated, are formed as a unitary device housed in a casing 12 as shown in Fig. 1, which casing is diagrammatically represented in Fig. 2 by the dot-dash line enclosing the pumping and governing mechanisms. Such embodiment of governing and pumping mechanisms in a single unitary structure is more particularly disclosed and claimed in my application Serial No. 141,327 filed May 7, 1937 (issued Sept. 10, 1940, as Patent No. 2,214,390).

The remote control means is composed of a plurality of independently operable valve means, each controlling or effecting a predetermined portion of the cycle of operation of the table. These valve means are associated with the governing mechanism of the device 11 and are independently controlled to obtain a desired cycle of operation.

The unitary pressure generating and control device 11 disclosed herein is the same as that disclosed in my Patent No. 2,214,390 and will thus be described briefly, reference being made to my

patent just referred to for a more complete disclosure of the precise formation and location, in a unitary structure, of the pumping mechanism, the governing mechanism and the passages and ducts interconnecting the same. Movement of the table at a high speed or "traverse" rate requires no high degree of uniformity and the fluid for effecting such movement may be supplied by any pump capable of a large output at the required pressure. Herein the rapid traverse pump 13 is shown as a constant displacement variable pressure pump of the rotary type, such as more particularly disclosed and claimed in my copending applications Serial No. 675,218, filed June 10, 15 1933, (issued October 11, 1938, as Patent No. 2,132,813) and Serial No. 14,017, filed April 1, 1935 (issued February 7, 1939, as Patent No. 2,146,037). The pump 13 is adapted to be continuously rotated during the operation of the 20 machine tool and functions in well known manner to draw fluid, preferably oil, into the pump from a tank or reservoir 20 through an intake pipe 21, an intake port 22 formed in the casing 12 and a port 23 of the pump and to discharge the 25 fluid through a port 24 into a passage 25 formed within the casing 12.

When the tool is in engagement with the work, that is, during the "feed" movement of the table, a slow uniform movement of the table is required 30 and necessitates the supply to the motor 10 of a small quantity of fluid at an accurately metered rate. The pump 14 for supplying such an accurately metered quantity of fluid herein takes the form of a variable displacement piston pump 35 of novel construction, more particularly described and claimed in my copending application Serial No. 60,646, filed January 24, 1936, now abandoned, and my Patent No. 2,214,390. This pump comprises a plurality of annularly disposed parallel cylinders 30, each having a piston 31 reciprocable therein which in all positions has one end projecting from the cylinder. The pistons 31 are actuated by a wobble plate 32 swiveled on a ball 33 and having an arm 34 projecting centrally of the cylinders into a socket 35 formed in the end of a drive shaft 36 oblique to the axis thereof. The pistons 31 merely abut the wobble plate 32 and are not positively connected thereto so that the wobble plate is capable of imparting an exhaust stroke only to the pistons but is unable to impart a return or intake stroke thereto, thus making the pump non-self-priming. Each cylinder 30 has an intake port and an exhaust port with the intake port controlled by a check valve 37 functioning to permit flow of fluid into the cylinder but preventing return flow out of the cylinder, and with the exhaust port controlled by a check valve 38 which functions to permit discharge from the cylinder but to prevent return flow into the cylinder. All of the intake ports open into a charging passage 39 communicating with the passage 25, and all of the exhaust ports open to a supply passage 40. Shaft 36 also drives the gear pump 13.

The displacement of the pump 14 may be varied by changing the stroke of the pistons 31 and this is accomplished by relative axial adjustment of the wobble plate 32 and the shaft 36. Such relative adjustment varies the extent to which the arm 34 is received in the oblique socket 35 thereby varying the throw of the wobble plate. This is accomplished by movement of the wobble plate 32, and to that end the ball 33 upon which the wobble plate is swiveled is formed on the end of a piston 41 slidable in the inner end of the bore

of a cylinder 42. The piston 41 may be manually set at a predetermined fixed displacement of the pump by means of cam rings 43 and 44 rotatable on the cylinder 42. To that end, there is secured diametrically of the piston 41 a rod 45 projecting through longitudinal slots 46 in the cylinder and between the rings 43 and 44. By rotation of the rings 43 and 44, the piston 41, by engagement of the rings with the rod 45, may be set in a predetermined position to obtain a fixed predetermined displacement of the pump. The rings 43 and 44 have worm teeth formed on their periphery and may be rotated by worms having knobs 47 and 48 (see Fig. 1) disposed outwardly of the casing 12 for convenient adjustment of the displacement of the pump.

The displacement of the pump 14 may also be varied automatically by hydraulic means. Herein this means is capable of adjusting the pump 14 to any one of three displacements and comprises in addition to the piston 41 and the cylinder 42 a second piston 49 reciprocable in the outer end of the bore of the cylinder 42 and adapted to abut the outer end of the piston 41 to shift the same. The piston 49 is limited in its inward movement by an adjusting rod 50 having a lost motion connection at its inner end with the piston 49 and fixed at its outer end in a cap 51 adjustably threaded upon the end of the cylinder 42. Opening to the outer end of the bore in the cylinder 42 is a port 52 threaded for the reception of a conduit, and opening to the bore intermediate the pistons 41 and 49 is a port 53 also threaded for the reception of a conduit. When the displacement of the pump 14 is to be varied automatically, the rings 43 and 44 are employed merely to limit the movement of the piston 41 and thus predetermine the maximum and minimum displacement to which the pump may be shifted automatically. The rings 43 and 44 are correspondingly rotated to permit movement of the piston 41 and are positioned to constitute stops against which the rod 45 abuts at the predetermined time in either the inward or the outward movement of the piston 41. Ring 43 determines the maximum displacement of the pump and the piston 41 is normally urged to the limit permitted by the ring 43 by the reaction of the fluid in the cylinders 30 on the pistons 31, while ring 44 determines the limit of inward movement of the piston 41 when fluid pressure is applied through the port 53 and thus determines the minimum displacement of the pump. The cap 51 and rod 50 controlling the inward movement of the piston 49 are proportioned and adjusted to limit the shift of the piston 49, and the corresponding shift of the piston 41, when fluid pressure is applied through the port 52, to a position of the piston 41 intermediate that determined by the rings 43 and 44 in order to obtain an intermediate displacement. The manner in which the fluid is supplied to the ports 52 and 53 will be described more fully hereinafter.

Having described the pumps constituting the pumping mechanism, the governing mechanism for controlling the functioning of the pumping mechanism and the volume, direction and pressure of discharge of fluid from the device 11 will now be described. As previously stated, the volume of discharge is controlled by valve means generally designated 15 and this means is composed of three independently operable valves disposed in a bore 55 extending transversely of the casing 12 and intersecting the passage 25 to which the gear pump 13 discharges. Immedi-

ately adjacent and on opposite sides of the passage 25, the bore 55 is formed with an annular groove 56 and an annular groove 57. Both grooves 56 and 57 communicate with a large passage 58 terminating in a return port 59 formed in the casing 12 opposite the intake port 22 and threaded for the reception of a return pipe 60 leading to the reservoir 20.

Flow of fluid from the passage 25 to the groove 56 is controlled by a valve 61 in the form of a hollow piston which functions as a start and stop valve as will later become more apparent. The valve 61 has two positions, namely, an open position as shown in Fig. 2 in which flow is permitted from the passage 25 to the groove 56 and a closed position determined by abutment of the valve with a plug 62 in which the head or closed end of the valve projects into the opening between the passage 25 and the groove 56 to prevent flow therethrough. The valve is normally urged to its closed position by means of a light compression spring 63 which is disposed within the valve with one end abutting the closed end of the valve and the other end abutting a plug 64 having a fluid-tight fit in the bore 55. Intermediate the groove 56 and the plug 64, the bore 55 is formed with a second smaller annular groove 65 and immediately adjacent the plug 64 a port 66 opens to the bore. By means of a passage 67, port 66 is connected to a first external control fluid port 1 threaded for the reception of a conduit, while groove 65 is connected by a duct 68 to the supply passage 40. Port 66 is always open and is not controlled by the valve 61, but groove 65 is controlled by valve 61 and to that end the valve is formed with an external annular groove 69 which is of such width and is so positioned on the valve as to effect communication between the groove 65 and the groove 56 when the valve is in open position but to close the groove 65 when the valve is in closed position. Dust 68 provides an escape for slippage fluid when the device 11 is not discharging fluid.

Communication between the passage 25 and the groove 57 likewise is controlled by a valve 70 in the form of a hollow piston, similar to the valve 61, which functions as a rate change or charging valve. This valve also has two positions, namely, a closed position in which the head end of the valve projects into the opening between the passage 25 and the groove 57 to prevent flow of fluid therethrough, which position is determined by abutment with the plug 62, as shown in Fig. 2, and an open position shifted to the left in Fig. 2, in which flow is permitted from the passage 25 to the groove 57. The valve is urged to its closed position by a heavy compression spring 71 substantially stronger than the spring 63, having one end abutting the closed or head end of the valve 70 and the other end abutting a cap 72 closing one end of the bore 55. Opening to the bore adjacent the cap 72 is a port 72'.

Each of the valves 61 and 70 is formed at its closed or head end with a small opening 73 to permit bleeding of fluid from passage 25 to the interior of the valve. This opening preferably is covered by a screen (not shown) to prevent clogging of the opening by foreign material.

As previously stated, the valve 61 functions as a start and stop valve, while the valve 70 functions as a rate change or charging valve, both valves governing the conditions which determine the manner in which the pump 14 functions.

The strength of the spring 63 controlling the valve 61 is such that when the fluid bleeding through the opening 73 is free to return to the reservoir 20 the valve normally maintains a low pressure in the passage 25, which is insufficient to open the intake check valves 37 of the variable displacement pump 14 and impart a return stroke to the pistons 31 thereof. Thus, when the valve is controlled by the spring 63 only, no discharge from the device 11 takes place for the valve 61 is opened by the low pressure of the fluid in the passage 25, thereby permitting escape of the fluid through the groove 56, passage 58, and out through the return pipe 60. Spring 71 of valve 70, under a similar condition, maintains a pressure in the passage 25, which may approximate 75 pounds, but in all events is sufficient to open the intake check valves 37 and impart a return stroke to the pistons 31 of the variable displacement pump 14. Thus, when controlled by the spring only, valve 70 functions to charge the pump 14 rendering the same operative to discharge fluid from the device in metered quantities, any excess of fluid supplied by the traverse pump being returned to the reservoir through passage 58 and pipe 60. Either or both of the valves 61 and 70 may be positively held in closed position by blocking the escape of the hydraulic fluid bleeding into the valves through the openings 73 formed in the end thereof. Such blocking causes the pressure on opposite sides of the valve to be equalized thereby rendering the spring capable of closing the valve. When valve 61 is positively held closed, discharge takes place from the device 11 as determined by the valve 70. If valve 70 is then closed only by spring 71, the valve functions to charge the pump 14 and the volume of discharge from the device is low as determined by the displacement of the feed pump 14, but if valve 70 is positively closed, the volume is large as determined by the displacement of the traverse pump 13. Valve 70 thus determines whether the table is driven at a "feed" or a "traverse" rate of movement, and unless valve 70 is positively held closed, positive closure of the valve 61 to initiate operation will start the table at a fast "feed" rate.

At its right end, the bore 55 is closed by a cap 75 having a third external control fluid port 3 opening therethrough and threaded for the reception of a conduit. An annular groove 76 opens to the bore 55 and communicates with a duct 77 which terminates in an external port 4 threaded for the reception of an external conduit #4 leading to the port 53 of the means for varying the displacement of pump 14. The end of the bore opposite the cap 75 is adapted to be connected to the reservoir to permit the exhaust of fluid returned through duct 77 and to that end is here shown formed with a port 78 connected by a duct 79 to the passage 58. Also opening to the bore 55 is a port 80 connected by a branch 68' of duct 68 to passage 40 for supplying high pressure fluid to the bore.

Reciprocable in the right end of the bore 55 is a valve 85, in the form of a hollow piston, controlling the supply of fluid to the port 53 of the means for varying the displacement of the variable delivery pump 14. The valve is yieldably urged to the right to the position shown in Fig. 2 by a compression spring 86 received in the valve and acting between the closed end of the valve and the plug 64. The valve is formed intermediate its ends with an annular external groove 87 and with radial apertures 88. These are so

located that with the valve in the position shown, the port 80 is closed but the apertures 88 register with the groove 76 to permit discharge to the passage 79 and thence to the reservoir of any fluid returned through the duct 77. However, when fluid pressure is applied to the right end of the valve through the port 3, the valve is shifted to the left and the groove 87 serves to connect the port 80 with the groove 76 to supply high pressure fluid to the port 53.

To accommodate the valve means, generally designated 16, controlling the direction of fluid discharge from the unitary device 11, the casing 12 is formed near the top with a transversely extending bore 90, closed at one end by a cap 91 and at the other end by a cap 92. Cap 91 has formed therein a fifth external control fluid port 5 threaded for the reception of a conduit. Substantially midway between its ends, the bore 90 has opening thereinto five annular and axially spaced grooves 93, 94, 95, 96, and 97. The intermediate one of these grooves 95 communicates by means of a large passage 98 with the supply passage 40. The grooves 94 and 96 on opposite sides of the groove 95 communicate respectively with large external ports 99 and 100 threaded for the reception of conduits leading to the hydraulic motor to be supplied with fluid. End groove 93 is connected by a passage 101 and a passage 102 to the end groove 97 and to the valve means controlling the return fluid, as will presently be described. Intermediate the groove 93 and the cap 91, the bore 90 is formed with a narrow holding groove 103 which is connected by a duct 104 with the passage 25 to which the gear pump 13 discharges. Intermediate the groove 97 and the cap 92, the bore 90 is formed with a narrow annular groove 105 which groove is connected by a passage 72' with the port 72' of the bore 55. Adjacent the groove 105 is an external port 2' threaded for the reception of a conduit.

Reciprocable in the bore 90 to control the various grooves, is a spool valve 106 provided with wide end lands 107 and 107' and two intermediate lands 107'', all spaced axially a distance embracing two grooves in the bore. Extending axially of the valve is a passage 108 communicating at one end by means of radial ports with a leakage groove 108' formed in the land 107 and opening at the other end into a recess 108'' formed in the end of the valve. The valve has two positions, namely, a "forward" position, shown in Fig. 2, to which it is urged by a compression spring 109 received at one end within the recess 108'', and a "return" position to which it is shifted by the application of fluid pressure through the port 5. It will be seen that in the "forward" position shown, grooves 94 and 95 are bridged so that the discharge from the variable delivery pump 14 is directed to the port 99, while grooves 96 and 97 are also bridged so that the return fluid entering through port 100 may be directed to the return fluid controlling valve means through passage 102. In this position, groove 105 and port 2' are bridged by a groove 109' formed in the land 107'. When shifted to the left to "return" position, groove 95 is then connected to groove 96 while groove 94 is connected to groove 93 to reverse the direction of discharge and return of fluid from and to the ports 99 and 100. In "return" position, groove 105 is blocked while groove 103 is now uncovered to permit the supply of fluid through duct 104 to hold valve 106 in shifted position.

To accommodate the remaining valve means 17, the casing 12 is formed with a transversely extending bore 110 disposed intermediate the bore 55 and the bore 90. The bore 110 has opening thereinto an annular groove 111 into which opens passage 102 communicating with the end grooves 93 and 97 of the reversing valve means. An annular groove 112 to the right of the groove 111 communicates by means of a passage 112' with the passage 58 and return port 59, and an annular groove 114 at the extreme right end of the bore also communicates by means of a passage 114' with the passage 58. Also opening to the bore 110 intermediate the grooves 112 and 114 is a groove 116 communicating with the supply passage 40 of the variable delivery pump 14. At the extreme left end of the bore is an annular groove 113 connected by a duct 113' with the passage 112' and by a duct 113'' with a port 115 opening to the bore 90 adjacent the cap 92. Thus, any fluid which happens to be in the left end of the bore 90 may be discharged to the reservoir when the valve 106 is shifted.

Interposed between the grooves 111 and 112 and suitably ported to communicate with the groove 111 is a centrally apertured member 117 forming a seat for a valve 118 controlling the return fluid. The valve 118 is slidably supported in a tubular member 119 received in the left end of the bore 110 and retained therein by means of a hollow cap 120 threaded into the end of the bore. Urging the valve 118 to seated position is a compression spring 121 which at one end bears against a flanged washer on the stem of the valve 118 and at the other end bears against a washer swiveled on the end of an adjusting screw 122. The member 119 has radial ports registering with the groove 113 to permit discharge of any fluid leaking along the valve 118.

It will be apparent that the valve 118 is not responsive to the pressure of the return fluid in the passage 102, and to actuate the valve 118, means is provided which is responsive to the supply fluid pressure only. Accordingly, there is received in the right end of the bore 110 a tubular member 125 retained in the bore by means of a hollow cap 126 threaded into the bore. The member 125 is suitably apertured to provide communication between the bore 114 and the interior of the member and is also apertured to provide communication between the interior of the member and the groove 116 communicating with the fluid supply passage 40. Interposed between the member 117 and the member 125 is a piston 127 having a point engaging the end of the valve 118 for the purpose of shifting the valve upon actuation of the piston 127. To subject the piston 127 to the supply pressure, but to prevent shifting thereof due to slight changes in pressure, the closed end of the member 125 is formed with a small bleed opening 128. Preferably, a screen (not shown) is positioned over the bleed opening to prevent foreign material from entering and clogging the same. It will be seen that the valve 118 and the piston 127 being responsive only to the supply pressure function as a circuit locking means and as a low pressure limit means. To the right of the apertures registering with the groove 116, the member 125 is formed to provide a seat for a disk valve 129 which serves as a relief valve. The valve is urged to seated position by means of a heavy compression spring 130 which abuts against a washer resting on an adjusting screw 131 threaded into the cap 126. This valve is adjusted to open only at extremely high pressures

for the purpose of avoiding injury to the system. It constitutes a high pressure limit.

The remote control means comprises a plurality of individual and independently operable valve means connected by means of conduits to the external ports of the device 11 so that each valve means controls one of the steps or stages of operation in the cycle of movement of the table 9. With this arrangement, an unusually flexible control is obtained, for the duration of a stage in the cycle is determined by the length of actuation of the valve means controlling that stage, and the presence or absence of a stage in the cycle likewise is controlled by the operation or non-operation of the particular valve means controlling such a stage.

Herein five such valve means are shown and are respectively designated SV, RV, TV, FIV and F2V. These valve means are generally similar, each having a casing 140 with a longitudinal bore formed therein and a valve 141 slidable in the bore. The valve 141 has a "normal" position to which it is urged by a compression spring 142 and a "shifted" position to which it is moved by suitable means in opposition to the spring 142. The valve means differ in the porting and grooving formed in the bore and the valve proper, with the exception that each casing is formed at its lower end with an exhaust port 140' connected to a common return conduit #9 leading to the reservoir 20.

The casing of the valve means SV is formed with a narrow annular groove 143 and a narrow annular groove 144 spaced axially from the groove 143 and both opening to the bore. The valve of the valve means SV is formed with two external annular grooves which in the "normal" position of the valve register with the grooves 143 and 144 of the bore and which communicate by means of radial ports with an axial passage opening through the lower end of the valve to the bore in the casing. In its "shifted" position, the valve blocks the grooves 143 and 144 to prevent any discharge from the grooves to the bore in the casing. Since the valve means SV is intended to control the starting and stopping of the table, the groove 143 thereof is connected by a conduit #1 to the external port 1 of the device 11 which port, as previously stated, is associated with the start and stop valve 61 to control the initiation and arrest of discharge of fluid to the motor 10. It will be apparent that with the valve of the start and stop valve means SV in "normal" position the conduit #1 is open to the reservoir and thus prevents the building up of pressure within the conduit. Valve 61 is thus held closed only by the spring 63 and no discharge to the motor takes place. With the valve 141 in "shifted" position, however, the conduit #1 will be blocked and thus initiate discharge of fluid to the motor 10.

The casing of the valve means TV is formed with but a single annular groove 145 opening to the bore therein, while the valve 141 is also formed with but a single annular groove which in the normal position of the valve registers with the groove 145 and which communicates by means of radial ports with an axial passage opening through the lower end of the valve to the bore in the casing. Since this valve means is intended to determine "traverse" operation of the motor 10, the groove 145 of the casing is connected by an external conduit #2 to the external port 2' of the device 11. This port, as previously described, in the forward position of the revers-

ing valve 106 is in communication with the interior of the charging or rate-change valve 70 through the duct 72'. From the foregoing, it will be apparent that when the valve of the traverse valve means TV is in "normal" position the conduit #2 is in communication with the reservoir 20 and thus there can be no building up of pressure of the fluid bleeding into the valve 70 and thus the valve 70 cannot be positively held in closed position. However, when the valve 141 of the traverse valve means is shifted, conduit #2 is blocked, thereby causing a building up of pressure within the valve 70, positively closing the same and causing the entire discharge of the "traverse" pump to be supplied to the motor 10 to effect a traverse rate of movement.

The casing of the valve means RV is formed with an annular groove 146 and an annular groove 147 opening to the bore, while the valve proper is formed with a wide annular groove 148. In the "normal" position of the valve proper the groove 148 registers with the groove 147, while the groove 146 is blocked, while in "shifted" position of the valve, groove 148 bridges the grooves 146 and 147 to effect communication therebetween. Since the valve means TV is intended to control the reversal of the table 9, the groove 146 is connected by an external conduit #5 to the external port 5 of the device 11 leading to the right end of the bore 90 of the reversing valve means. Groove 146 is also connected by a short external conduit #5' to the groove 144 of the start and stop valve means SV, while groove 147 is connected by means of an external conduit #6 to the external port 6 which leads to the passage 25 to which the traverse pump 13 discharges. Conduit #6 serves as a control fluid supply conduit. From the foregoing it will be seen that when the valve of the reversing valve means RV is in "normal" position, the conduit #6 is blocked, while the conduit #5 is open to the reservoir through the groove 146 of the valve means RV, conduit #5', groove 144 and axial passage of the valve means SV and return conduit #9, thereby permitting the discharge of fluid from the right end of the bore 90 when the valve 106 is being urged to "forward" position by the spring 109. The communication of the conduit #5 with the reservoir 20 presupposes valve 141 of the start valve means SV in "normal" position, for in "shifted" position the groove 144 is blocked, as previously described. In "shifted" position, groove 148 of the reversing valve means bridges the grooves 146 and 147, thereby causing the supply of control fluid to the bore 90 of the reversing valve means for shifting the valve 106 to its "return" position, valve SV being in its shifted position.

The casing of valve means F1V is formed with narrow, axially spaced grooves 149 and 150 opening to the bore therein, while the valve proper is formed with a wide annular groove 151 near its lower end and spaced upwardly therefrom with a narrow groove communicating by means of radial ports with an axial passage opening through the lower end of the valve to the bore in the casing. In the "normal" position of the valve, the narrow annular groove registers with the groove 149 in the casing, while in the "shifted" position of the valve the wide annular groove 151 serves to bridge the grooves 149 and 150 to effect communication therebetween. Since the valve means F1V is intended to control the slow feed movement of the table 9, the groove 149 is connected by an external conduit #3 with the

external port 3 of the device 11 communicating with the slow feed valve 85 to control the position thereof. Groove 150 is connected to an external conduit #6' which is a branch of the control fluid supply conduit #6. It will be apparent from the foregoing that with the valve of the slow feed valve means F1V in "normal" position conduit #3 is open to the reservoir through the groove 149 and the axial passage in the valve proper, thereby permitting the slow feed valve 85 to be shifted to its normal position by the spring 86 with the result that no fluid pressure is supplied through conduit #4 to shift the piston 41 of the displacement varying means. When the valve is in "shifted" position, however, control fluid is supplied to the port 3 through conduit #6', groove 151 and conduit #3 with the result that valve 85 is shifted and high pressure fluid is applied to the piston 41 for shifting the same inwardly to reduce the displacement of the variable delivery pump 14 to a minimum.

The last of the valve means F2V is identical with the slow feed valve means and, accordingly, the casing is formed with narrow axially spaced grooves 152 and 153 opening to the bore, while the valve proper is formed at its lower end with a wide annular groove 154 and a narrow annular groove spaced upwardly from the wide groove and communicating by means of radial ports with an axial passage opening through the lower end of the valve to the bore in the casing. Here again in "normal" position, the narrow annular groove of the valve registers with the groove 152 of the casing, while in "shifted" position the wide annular groove 154 of the valve bridges grooves 152 and 153 to effect communication therebetween. In this instance, the groove 152 is connected by an external conduit #7 to the port 52 of the displacement varying means, while groove 153 is connected by an external conduit #8 to the high pressure fluid supply passage 40. It will be seen that in the "normal" position of the intermediate feed valve means conduit #7 is open to the reservoir, while in shifted position conduit #7 is connected by means of conduit #8 to the fluid supply passage 40 thereby causing a discharge of high pressure fluid through the port 52 for acting upon the piston 49 which is then shifted inwardly to the extent permitted by the adjustable rod 50 for setting the displacement of the pump 14 at some intermediate value.

The hydraulic circuit is completed by the conduits leading from the device 11 to the motor 10. Herein the motor is of the reciprocating type and comprises a cylinder 160 in which is reciprocable a piston 161 connected by a rod 162 to the table 9. The head end of the cylinder 160 is connected by a conduit 163 to the external port 99, while the rod end of the cylinder is connected by a conduit 164 to the external port 100 of the device 11.

While the remote control valve means may be shifted by a variety of means, and while a variety of cycles of movement of the table 9 may be obtained by a different sequence in the actuation of the valve means, or by a variation in the duration of actuation, or by the total omission of one or more of the valve means, they are herein shown as actuated electrically in a manner to obtain a cycle of operation including rapid approach, fast feed, intermediate feed, slow feed, rapid return and stop. Accordingly, each of the valve means is provided with a coil 166 operable upon energization to move the valve 141 to "shifted" position against the opposition of the spring

142. One end of each of the coils 166 is connected to a line wire L1, while the remaining ends of the coils 166 are adapted to be connected through manual or dog actuated switches to a line wire L2.

Herein, the remaining end of the coil 166 of the start and stop valve means SV is connected to the line wire L2 through a dog actuated stop switch SS, biased to closed position, and a manual push button switch SS', biased to open position, connected in parallel with the dog actuated switch. The coil of the reversing valve means RV is likewise connected to the line wire L2 through a dog actuated switch RS, biased to open position, and a manual push button switch RS' also biased to open position and connected in parallel with the dog actuated switch RS. The coils of the valve means TV, F1V and F2V are connected to the line wire L2, respectively, by dog actuated switches TS, F1S and F2S, each biased to open position.

As previously stated, the cycle of operation which is here illustrated by way of disclosing the invention includes rapid approach, fast feed, intermediate feed, slow feed, rapid return and stop. Accordingly, the table 9 carries a stop dog SD, a reversing dog RD, a traverse dog TD, a slow feed dog F1D, and an intermediate feed dog F2D disposed to control the corresponding switches and positioned and shaped to cause the energization or deenergization of the coils 166 of the respective valve means at the proper time and for the proper duration to obtain the various movements in the proper sequence and for the proper length of time.

With the cycle of operation mentioned, the stop dog SD is disposed to engage and open the switch SS controlling the start and stop valve SV when the table arrives at the end of its return movement, while the traverse dog TD, controlling the traverse switch TS, in the stop position of the table shown, engages the switch to close and to maintain the same closed during the extent of movement of the table in a forward direction during which rapid traverse is desired.

The operation of the various valves and the flow of fluid through the circuit is best understood from the following brief description of the operation. Let it be assumed that the table is in its stop position shown and that dog SD has opened switch SS and dog TD has closed switch TS. To initiate movement of the table, the operator depresses the push button switch SS', thereby energizing the coil 166 of the start valve means SV, with the result that the conduit #1 is now blocked causing fluid pressure to build up within the start valve 61, whereby the spring 63 positively maintains the same closed to initiate discharge of fluid from the device 11 to the motor 10. The push button switch SS' is held closed by the operator until the dog SD has released the switch SS and permitted the same to close. It will be apparent that the switch SS is maintained closed throughout the cycle of movement of the table, thereby maintaining the valve 141 of the start valve means in "shifted" position to maintain the conduit #1 blocked and start valve 61 positively closed throughout the cycle of movement of the table.

It has been presupposed that the traverse switch TS would be closed by the traverse dog TD with the result that the valve of the traverse valve means VT is shifted to block the conduit #2. As a result, pressure is built up in that con-

duit and hence spring 71 maintains the charging and rate change valve 70 positively closed so that the entire discharge of the "traverse" pump 13 is caused to pass through the feed pump 14 and to be discharged to the motor 10. With the valve 106 in "forward" position, this discharge of a large volume of fluid will be to the head end of the cylinder 160 through the conduit 163, thereby initiating movement of the table in a forward direction at a traverse rate, i. e. rapid approach.

After a predetermined travel of the table 9 determined by the length of the traverse dog TD, the switch TS will be opened with the result that the coil of the traverse valve means TV will be deenergized and the valve thereof returned to "normal" position. In this position, conduit #2 is connected to the reservoir 20 through the conduit #9 with the result that the charging and rate change valve 70 is now urged to closed position only by the spring 71. Under that condition, the valve 70 serves merely to charge the "feed" pump 14, that is, the valve 70 maintains a pressure in the passage 25 and the charging passage 39 which is sufficient to open the intake check valves 37 of the pump 14 and impart a return stroke only to the pistons 31 thereof. The pressure of the fluid in the passage 25, however, is not high enough to open the exhaust check valves 38 against the pressure in the passage 40 so that the "feed" pump functions to meter the quantity of fluid discharged to the passage 40 and also to raise the pressure thereof. The displacement of the "feed" pump 14 is now at the maximum for which it has been preset by rotation of the ring 43, with the result that table 9 is now driven at a fast feed rate in a forward direction. Any excess of fluid supplied by the "traverse" pump over that metered by the "feed" pump 14 is discharged to the reservoir 20 through the groove 51, passage 58 and return pipe 60.

Fast feed movement of the table 9 continues until the intermediate feed dog F2D engages and closes the intermediate feed switch F2S. When this switch is closed, the valve of the intermediate feed valve means F2V is shifted with the result that high pressure fluid is supplied to the port 52 of the displacement varying means through the conduit #8 and the conduit #7. This causes the piston 49 to be shifted inwardly and imparts a corresponding movement to the piston 41 to change the displacement of the pump 14. The extent of movement is limited and adjusted to provide some intermediate displacement with the result that the table 9 is now driven at an intermediate feed rate in a forward direction.

Feed movement of the table at an intermediate rate continues until the slow feed dog F1D engages and closes the slow feed switch F1S thereby causing the slow feed valve means F1V to be shifted out of normal position. With the slow feed valve means in shifted position, conduit #3 is connected to the control fluid supply conduit #6', with the result that the slow feed valve 85 is shifted to connect port 80 and groove 76. High pressure fluid from the passage 40 is then supplied through the conduit #4 to the port 53 of the displacement varying means causing the piston 41 to be shifted inwardly to the full extent permitted by the previous adjustment of the cam ring 44 with the result that the displacement of the pump 14 is reduced to a minimum and the table 9 is now moved at a slow feed rate of movement.

At the end of the slow feed rate of movement

of the table 9, the reversing dog RD engages and closes the reversing switch RS thereby causing the valve 141 of the reversing valve means RV to be shifted. This causes grooves 146 and 147 of the reversing valve means to be bridged by the groove 148 of the valve 141 with the result that control fluid is now supplied through the conduit #6 and conduit #5 to the right end of the bore 90 of the reversing valve means, thereby shifting the reversing valve 106 to the left to its "return" position. In its "return" position, valve 106 uncovers the groove 103 so that pressure fluid is supplied to the bore 90 through the groove 103 and the duct 104 to hold the valve in "return" position even though the reversing valve means RV is only temporarily shifted. Escape of fluid out of the conduit #5 is prevented because the groove 144 of the start and stop valve means SV is blocked.

With the valve 106 shifted to "return" position, groove 95 is now in communication with groove 98 while groove 94 is in communication with groove 93 so that pressure fluid is now supplied to the rod end of the cylinder 160, while fluid from the head end is discharged through the conduit 163, grooves 94 and 93, passages 101 and 102 to the valve 118. In "return" position, valve 106 also blocks groove 105 thereby causing pressure to build up in the duct 72" and hence spring 71 maintains the valve 70 in closed position regardless of the position of the traverse valve TV. As a result, the entire discharge of the "traverse" pump 13 is now supplied to the motor, thereby driving the table at a traverse rate in a return direction.

When the table returns to stop position, the stop dog SD engages the switch SS which has been closed during the entire cycle to open the same and deenergize the coil 166 of the start and stop valve means SV. The valve 141 of the start and stop valve means SV is then returned to "normal" position by the spring 142 connecting both grooves 143 and 144 to the reservoir. The result is that the pressure fluid in the conduit #1 is relieved thereby placing the start valve 61 solely under the control of spring 63 which then maintains a pressure insufficient to open the intake check valves 37 of the feed pump 14 so that no fluid is discharged to the motor and the table is brought to rest. The fluid in the right end of the bore 90 of the reversing valve means also is free to discharge to the reservoir so that spring 108 now functions to return the reversing valve 106 to its "forward" position. The fact that during the return movement of the table the traverse dog TD engaged and closed the switch TS is immaterial because the duct 72" already was blocked by the valve 106 and additional blocking of the conduit #2 by the traverse valve means causes no change in the operation. By manual closure of the push button switch RS', the table may be reversed at traverse rate at any time during the cycle.

Regardless of the direction of movement of the table 9, the return fluid from the motor 10 is directed by the passage 102 to the bore 110 where its return to the reservoir is controlled by the valve 118. This valve, as previously stated, is not responsive to the pressure of the return fluid, but is responsive solely to the pressure of the supply fluid in order that it may function to prevent overrunning of the table during a climb cut or when the tool breaks through the work. Preferably, the spring 121 is so adjusted that the valve 118 is opened to permit substantially unrestricted

discharge when the pressure of the supply fluid is equal to or in excess of that required to move the table at a traverse rate and under no load. This pressure is always less than the pressure required to move the table at a traverse rate and under no load, which pressure is always less than the pressure required to move the table during a normal cut of the tool and thus during traverse movement of the table in either direction and during a normal feed movement the valve 118 is open permitting substantially unrestricted discharge from the passage 102 through the passage 112 to the passage 58 and then out through the return pipe 60. During a climb cut, however, when the tool tends to advance the table at a rate faster than that which is determined by the discharge of fluid by the pump 14, the supply pressure drops below the predetermined value for which the valve 118 is set, thereby permitting the valve to close or at least restrict the flow of return fluid so as to prevent overrunning of the table and causing the rate of movement to be determined by the rate at which fluid is supplied to the motor by the pump 14. Should the table become obstructed, as during a dwell when the table engages a positive stop, the supply pressure builds up in the passage 40 and eventually opens the relief valve 129 permitting discharge of the fluid to the reservoir through the passages 114', 58 and return pipe 60.

With this character of remote control means, it is possible to obtain a dwell of the table prior to reversal without addition of further valve means or without modification of the present valve means simply by the incorporation of a definite time relay TR in the control of the reversing valve means RV. A fragmentary portion of the electrical control means including the definite time relay TR is shown in Fig. 3. The relay is of well known construction and is connected by a lead 170 to the line wire L1 and by a lead 171 to one of the stationary contacts of the switch RS. A third terminal of the relay is connected by a lead 172 to one end of the coil 166 of the valve means while the other end of the coil is connected to the line wire L1. The relay functions upon closure of the switch RS to delay the energization of the coil 166 a predetermined length of time. As a result, when the reversing dog RD engages the reversing switch RS and closes the same, the valve 141 of the reversing valve means RV is not immediately shifted but is delayed during the desired dwell period. When the time relay is employed, a conventional positive stop, not shown, is also provided with which the table 9 abuts at the beginning of the dwell period.

It is believed apparent from the foregoing that I have provided a unique form of remote control means which provides an unusually flexible control because each valve means is independent in its operation, in its control, and in its construction. This enables any desired number of valve means to be employed and permits each to be actuated at a predetermined point in the movement of the table and for a predetermined length of time simply by the proper location of a dog of suitable length. By controlling the valves electrically they may be mounted on the machine tool adjacent the pressure generating and control device and need not be mounted immediately adjacent the table.

I claim as my invention:

1. In combination with a member to be driven, a hydraulic actuator system for driving the same comprising a motor, pumping mechanism operable

to discharge fluid under pressure to said motor and governing mechanism associated with said pumping mechanism to determine the direction and volume of fluid discharge therefrom, electrically actuated remote control means hydraulically connected with the governing mechanism to control the same including a normally open manual switch operable upon closure to initiate discharge of fluid from the pumping mechanism to impart movement to the member, a normally closed dog actuated switch, a dog for holding said switch open when the member is in its stop position, said dog being withdrawn and said switch closed upon initiation of movement of the member to maintain discharge of fluid from the pumping mechanism, a second dog actuated switch operable while closed during movement of the member to cause a particular rate of movement of the member, and a third dog actuated switch closed at the end of movement of the member in the first direction and operable upon closure to effect a reversal in the direction of fluid discharge from the pumping mechanism to effect a reversal in the direction of movement of the member.

2. In a hydraulic actuator for driving a member at different rates of movement and in opposite directions, in combination, a reservoir, a hydraulic motor operatively associated with the member for driving the same, pumping mechanism operable to draw fluid from the reservoir and to discharge the same under pressure to the motor, governing mechanism associated with said pumping mechanism for determining the direction and volume of fluid discharge by the pumping mechanism to the motor including a hydraulically controlled start and stop valve, a hydraulically controlled rate change valve, and a reversing valve biased to forward position adapted to be hydraulically shifted to return position, and remote control means comprising a start and stop valve means hydraulically connected to the start and stop valve of the governing mechanism to control the same, a traverse valve means hydraulically associated with the rate change valve of the governing mechanism to control that valve, a reversing valve means hydraulically associated with the reversing valve of the governing mechanism to effect shift thereof to return position, and electrical control means for actuating said remote control valve means comprising a solenoid for each of said valve means, a dog actuated switch biased to closed position and a push button switch biased to open position connected in parallel with said dog actuated switch for controlling the energization of the solenoid of the start and stop valve means, a dog actuated switch biased to open position and a push button switch biased to open position connected in parallel with said last named dog actuated switch for controlling the energization of the solenoid of said reversing valve means, and a third dog actuated switch biased to open position and connected in series with the solenoid of said traverse valve means.

3. In combination with a member to be driven, a hydraulic actuator system for driving the same comprising, in combination, a motor, pumping mechanism operable to discharge fluid under pressure and at different volumes to said motor, governing mechanism associated with said pumping mechanism to determine the direction and volume of fluid discharge therefrom including a valve for controlling the rate of fluid discharge from said pumping mechanism, and electrically actuated remote control means hydraulically con-

nected with the governing mechanism to control the same including a normally open manual switch operable upon closure to initiate discharge of fluid from the pumping mechanism to impart movement to the member, a first dog actuated switch controlling said rate valve and operable while closed during movement of the member to cause a particular rate of movement of the member and operable when open to cause said pumping mechanism to discharge at a different rate, and a second normally open dog actuated switch closed at the end of movement of the member in the first direction and operable upon closure to effect a reversal in the direction of fluid discharge from the pumping mechanism to effect reversal in the direction of movement of the member.

4. In combination with a member to be driven, a hydraulic actuator system for driving the same comprising, in combination, a motor, pumping mechanism operable to discharge fluid under pressure to said motor, governing mechanism associated with said pumping mechanism to determine the volume of fluid discharge therefrom, and electrically actuated remote control means hydraulically connected with the governing mechanism to control the same including a normally open manual switch operable upon closure to initiate discharge of fluid from the mechanism to impart movement to the member, a first dog actuated switch operable while closed during movement of the member to cause a traverse rate of movement of the member, and a second dog actuated switch operable upon closure, and when said first dog actuated switch is open, to cause a feed rate of movement of the member.

5. In combination with a member to be driven, a hydraulic actuator system for driving the same comprising, in combination, a motor, pumping mechanism, including a variable displacement pump having a hydraulically actuated volume changing device, operable to discharge fluid under pressure and at different volumes to said motor, valve mechanism associated with said pumping mechanism to determine the direction and volume of fluid discharge therefrom, and electrically actuated remote control means hydraulically connected with said valve mechanism to control the same including a valve governing the supply of fluid to said volume changing device, a normally open manual switch operable upon closure to initiate discharge of fluid from the pumping mechanism to impart movement to the member, a dog actuated switch operable while closed during movement of the member to cause a traverse rate of movement of the member, a second dog actuated switch governing said valve and operable upon closure to cause fluid to be supplied to said volume changing device, and a third dog actuated switch closed at the end of movement of the member in the first direction and operable upon closure to effect a reversal in the direction of fluid discharge from the pumping mechanism to effect reversal in the direction of movement of the member.

6. In a hydraulic actuator system for driving a member at different rates of movement and in opposite directions, in combination, a hydraulic motor operatively associated with the member for driving the same, pumping mechanism operable to discharge fluid under pressure to the motor, governing mechanism associated with said pumping mechanism for determining the direction and volume of fluid discharge by the pumping mechanism to the motor including a hydraulically controlled start and stop valve, a hydraulically con-

trolled rate change valve, and a reversing valve adapted to be hydraulically shifted from a forward to a return position, remote control means comprising a start and stop valve means hydraulically connected to the start and stop valve of the governing mechanism to control the same, a traverse valve means hydraulically associated with the rate change valve of the governing mechanism to control that valve, a reversing valve means hydraulically associated with the reversing valve of the governing mechanism to effect shift thereof to return position, and electrical control means for actuating said remote control valve means comprising a solenoid for each of said valve means, a push button switch biased to open position for controlling the energization of the solenoid of the start and stop valve means, a dog actuated switch biased to open position for controlling the energization of the solenoid of said reversing valve means, and a dog actuated switch biased to open position for controlling the energization of the solenoid of said traverse valve means.

7. In a hydraulic actuator system for driving a member at different rates of movement and in opposite directions, in combination, a hydraulic motor operatively associated with the member for driving the same, pumping mechanism operable to discharge fluid under pressure to the motor, governing mechanism associated with said pumping mechanism for determining the direction and volume of fluid discharge by the pumping mechanism to the motor including a hydraulically controlled start and stop valve, a hydraulically controlled rate change valve, and a reversing valve adapted to be hydraulically shifted from a forward to a return position, remote control means comprising a start and stop valve means hydraulically connected to the start and stop valve of the governing mechanism to control the same, a traverse valve means hydraulically associated with the rate change valve of the governing mechanism to control that valve, a reversing valve means hydraulically associated with the reversing valve of the governing mechanism to effect shift thereof to return position, and electrical control means for actuating said remote control valve means comprising a solenoid for each of said valve means, a dog actuated switch biased to closed position for controlling the energization of the solenoid of the start and stop valve means, a dog actuated switch biased to open position for controlling the energization of the solenoid of said reversing valve means, and a third dog actuated switch biased to open position for controlling the energization of the solenoid of said traverse valve means.

8. In a hydraulic actuator system for driving a member at different rates of movement and in opposite directions, in combination, a hydraulic

motor operatively associated with the member for driving the same, pumping mechanism operable to discharge fluid under pressure to the motor, governing mechanism associated with said pumping mechanism for determining the direction and volume of fluid discharge by the pumping mechanism to the motor including a hydraulically controlled start and stop valve, a hydraulically controlled rate change valve, and a reversing valve adapted to be hydraulically shifted from a forward to a return position, remote control means comprising a start and stop valve means hydraulically connected to the start and stop valve of the governing mechanism to control the same, a rate change valve means hydraulically associated with the rate change valve of the governing mechanism to control that valve, a reversing valve means hydraulically associated with the reversing valve of the governing mechanism to effect shift thereof to return position, and electrical control means for actuating said remote control valve means comprising a solenoid for each of said valve means, a first dog actuated switch for controlling the deenergization of the solenoid of the start and stop valve means, a second dog actuated switch for controlling the energization of the solenoid of said reversing valve means, and a third dog actuated switch for controlling the energization of the solenoid of said traverse valve means.

9. In a hydraulic actuator system for driving a member at different rates of movement and in opposite directions, a hydraulic motor operatively associated with the member for driving the same, pumping mechanism operable to discharge fluid under pressure to the motor including a variable displacement pump, means for determining the direction and volume of fluid supplied by the pumping mechanism to the motor comprising a first valve operable to effect the initiation and arrest of fluid supplied to the motor, a second valve operable to condition the pumping mechanism to discharge fluid to the motor at a rate causing a traverse movement of the member, a third valve governing the direction of flow of fluid from the pumping mechanism to the motor when the pumping mechanism is supplying fluid to the motor, and a fourth valve operable to condition the pumping mechanism to supply fluid to the motor causing a feed movement of the member when said second valve is inoperative to obtain a traverse movement of the member, and a plurality of individually operable two-position remote control valves, each connected in controlling relation with one of said first mentioned valves and each spring biased to one of its two positions, each of said remote control valves when moved to the other of its positions effecting the operation of the valve with which it is connected.

GUNNAR A. WAHLMARK.
